HEATING SYSTEM

Daniel H. Keck, Appleton, Wis., assignor to Paper Patents Company, Neenah, Wis., a Corporation of Wisconsin

Application April 3, 1930. Serial No. 441,196

1 Claim. (Cl. 34—4)

The invention relates to improvements in heating systems and, although susceptible of other applications, it is of particular value in connection with the drying equipment of paper making machinery.

In the ordinary type of paper making machine having a Fourdrinier wet end, the drying of the formed web is effected by passing the latter around and in contact with the periphery of a series of rotating drums or cylinders which are heated by steam admitted to the interior of said drums. Usually there are a great number of such drums over or around which the paper web travels successively until the drying is completed.

Each of the drying cylinders is hollow and is equipped with a hollow trunnion or journal through which, by means of suitable gland connections, steam is admitted and the condensed water withdrawn. Obviously, from many stand-

points, it is desirable to employ a single steam source for supplying steam to all of the heating cylinders or at any rate, to divide the entire series of cylinders into a comparatively few groups or sections, each served from a single steam source. Similarly, it is desirable to conduct the condensate from a plurality of cylinders to a common receiver or outlet.

It will be manifest that in operating a series of heater units of this character it is required, for reasons of economy and control, that each dryer be made an independent unit, and that for reasons of economy steam should not be allowed to blow through from the cylinder directly into the outlet, nor should the condensate be allowed to accumulate in the cylinder, and thus reduce its heating efficiency and increase the power load. Various expedients have been employed or suggested in order to take care of these conditions, but aside from the employment of a large number of steam traps for the series of cylinders, I am not aware of any system which will at all times satisfactorily prevent the objectionable blowing through of steam from one or more cylinders of the series, in addition to which even with the steam trap arrangement, the removal of condensate is frequently found to be ineffective or incomplete and furthermore, because of direct contact of steam with the trap, steam is wasted in the ordinary operation of the trap.

The principal object of the present invention is to provide an arrangement which is particularly serviceable for drying equipment of the general character described, without the necessity of employing complicated traps or other analogous equipment for removing condensate and which will effectively prevent the blowing through of steam and will effect proper removal of the condensate without waste of steam while at the same time the apparatus is susceptible of use with a large number of drying units; to provide an

arrangement of the character specified which can be readily set or adjusted to suit widely varying conditions and which will maintain its efficiency when so adjusted, although the drying conditions such as steam pressure and consumption of steam, i. e. delivery of condensate, may be varied within wide limits; to provide an arrangement of the character specified which will operate satisfactorily with a large number of independent heater units supplied from a common steam source and discharging the condensate into a common outlet, to provide an arrangement which is free from moving parts or other complexities of design and operation and which may be manufactured, installed and operated at relatively low cost, and in general, to provide a simple, economical, efficient, and durable arrangement of the general character referred to.

In the drawing which illustrates my invention as applied to a single cylinder of the series with which a paper machine is equipped—

Fig. 1 is a somewhat diagrammatic section taken vertically through the cylinder and the associated parts of my improved equipment, and

Fig. 2 is an enlargement of parts of said equipment, portions thereof being broken away to illustrate the construction clearly.

Referring to the drawing, 10 represents somewhat diagrammatically a rotating drying cylinder which is supported at its ends by means of trunnions, one of which 11 is hollow and receives steam through a gland connection communicating with a pipe 12. The main steam supply pipe 12a is connected in common to a plurality or series of said branch pipes 12, each serving one of the cylinders of the series.

Extending down towards the bottom of the drying cylinder 10, there is located within said cylinder an intake leg 13 in the form of a curved pipe of relatively small diameter compared with the diameter of the trunnion 11 and having an intake opening 14, located close to the bottom of the interior periphery of the cylinder and through which opening the condensate is withdrawn. The upper end of said discharge leg 13 extends through the trunnion 11 and communicates at its outer end with the upper end of a downwardly extending preferably vertical discharge leg 15. The lower end of said discharge leg 15 communicates with a receiving well or pipe 16 of relatively large capacity which may discharge directly into the atmosphere or into a hot well.

The lower portion of the pipe 15 may be of a diameter comparable with that of the intake leg 13 and at its lower end is provided with a valve 17 by which the flow of condensate through said discharge leg 15 and into the common outlet 16 may be restricted. In the upper portion of the discharge leg 15, there is an enlargement pref-

erably in the form of a pipe 18 of diameter considerably larger than the pipe 13 and which enlargement preferably extends as far as the upper end of the intake leg 13 or at any rate to a point not much lower than the trunnion. At the lower end of said enlargement 18 there may be located a fitting 19 equipped with a sight-glass 20 through which the flow of condensate past the lower end of the enlargement may be observed.

If desirable, the enlargement 18 may be equipped with a blow-off cock 21 through which occluded air may be withdrawn or discharged if desired, when the steam is turned on at the commencement of a run. However, in normal operation, the cock 21 is kept closed.

The length of the discharge leg 15 below the sight-glass fitting 19 is such that there is a considerable difference in elevation between the valve 17 and the enlargement, said length or height of the discharge leg 15 serving as a balancing arrangement which will automatically control the flow of condensate through the restriction valve 17 in accordance with the amount of condensate which is supplied or withdrawn through the intake leg 13. This comes about by reason of the fact that the enlargement 18 effectively prevents siphoning through the U-shaped conduit comprising the parts 13, 18 and 15. It will be obvious that if the entire length of said U-shaped conduit were of comparatively small diameter, the same would become filled with fluid and so long as the same was full there would be a siphoning effect caused by the valve 17 being at a lower elevation than the intake opening 14 of said conduit in addition to which the pressure of steam within the cylinder 10 if above that of the atmosphere, which is customary, would further tend to aggravate the siphoning effect in view of the fact that the receiving pipe 16 is at substantially atmospheric pressure.

In operation it is found that by reason of the enlargement 18 the condensate when it reaches the outer end of the discharge leg 13 merely trickles down the interior of the enlargement 18 which is of sufficient cross sectional area to prevent it filling with fluid. Thus, there is always a space between the upper end of the enlargement 18 and some point in the lower end 15 of the discharge leg and there is no siphoning effect. Hence, the blowing through of steam is prevented. Furthermore, the enlarged chamber causes a lowering of pressure, due to its increased radiating surface, thus encouraging the flow of condensate. Also, elimination of siphoning facilitates removal of condensate without waste of steam. Usually the valve 17 is so adjusted that the column of water in the discharge leg 15 is at or slightly below the sight-glass 20 when the drying unit is operating at its maximum capacity. It is obviously necessary to adjust the valve 17 so that the column of water in the discharge leg 15 will not rise until it effects a solid connection with the water in the outer end of the intake leg 13. It will be understood that it is also desirable not to open the valve 17 to such an extent as to destroy the sealing of the valve by the column of condensate in the lower end of the discharge leg 15.

It is manifest that with the above arrangement the absolute pressure at the outer or upper end of the intake leg 13 will at all times be of substantially the same value as the pressure at the

upper end of the column of water in the discharge leg 15, whatever may be the height of said column. Therefore, the effective pressure tending to force the condensate through the restriction valve 17 will be the effective pressure of the steam, plus the height of the water column in the discharge leg 15, minus the difference in the elevation between the intake opening 14 and the center of the cylinder trunnion, neglecting minor factors such as friction. Hence, for an effective pressure of one pound of steam in a four or five foot cylinder the effective pressure across the valve 17 will be about equal to the height of the water column in the discharge leg 15. Hence, if the level of water rises in the cylinder 10 the negative factor of the equation will be reduced, the flow of condensate up through the intake leg 13 will be increased, and will tend to fill up the pipe 15, thus increasing the effective pressure across the valve 17 and the discharge of condensate into the outlet 16 will be correspondingly accelerated.

From a consideration of the foregoing, it will be understood that in order to provide a self-regulating arrangement, and to prevent blowing through of steam, it is preferable to so arrange the length 100 of the pipe 15 in relation to the restriction of the valve 17 so that even if perchance at any time there should be insufficient condensate to fill the intake leg 13 and thereby cause sucking, the opening of valve 17 would still be insufficient to 105 effect a complete removal of condensate from the lower end of the discharge pipe 15 before an additional supply was received through the intake leg 13 in order to supply the deficiency.

In practice, I have found that where an effective steam pressure of from 1 to 5 pounds is employed and where the web is say 12 feet in width, with a four foot drying cylinder, the intake leg 13 and the lower part of the discharge leg 15 may be of $\frac{3}{4}$ " pipe size while the enlargement 115 18 may be of $1\frac{1}{4}$ " pipe size, or somewhat larger, if desired. In such case, I have found that when using a $\frac{3}{8}$ " gate valve 17, a height of six feet between the sight-glass 20 and the valve would be sufficient to take care of all ordinary conditions 120 without the necessity of repeatedly adjusting the valve.

While I have shown and described my invention in a preferred form, I am aware that various changes and modifications may be made without departing from the principles of my invention, the scope of which is to be determined by the appended claim.

I claim as my invention:

In combination, a receptacle normally sealed 130 from the atmosphere, means for supplying steam to said receptacle for heating the same, a pipe having an intake leg communicating with the bottom portion of said receptacle and provided with a substantially vertical discharge leg extending to a discharge end, a valve disposed in said discharge leg, said discharge leg intermediate of its length having an enlarged portion of a vertical length at least substantially as great as that of said intake leg so as to prevent siphoning from 140 said receptacle, and said discharge leg between said enlarged portion and said valve being relatively long so as to serve as a balance which will automatically control the flow of condensate through said valve in accordance with the amount 145 of condensate being formed in said receptacle.

DANIEL H. KECK.
